UNITED STATES PATENT OFFICE.

GUY SPRINGER JENKINS, OF WATERBURY, CONNECTICUT, ASSIGNOR TO AMERICAN RING COMPANY, OF WATERBURY, CONNECTICUT, A CORPORATION OF CONNECTICUT.

DESIGN FOR A CASSEROLE.

48,112.

Specification for Design.

Patented Nov. 9, 1915.

Application filed August 23, 1915. Serial No. 46,967. Term of patent 7 years.

To all whom it may concern:

Be it known that I, GUY SPRINGER JENKINS, a citizen of the United States, residing at Waterbury, in the county of New Haven and the State of Connecticut, have invented a new, original, and ornamental Design for Casseroles, of which the following is a specification.

The design is shown in the accompanying drawing and in which the figure is a perspective view of a casserole showing my new design.

I claim:

The ornamental design for a casserole as shown.

GUY SPRINGER JENKINS.
